AIR BLOWING-VACUUMING DESOLDERING APPLIANCE OR THE LIKE

William S. Fortune, 14250 Dearborn St.,
Panorama City, Calif. 91402

Filed Nov. 27, 1974, Ser. No. 527,645

Term of patent 14 years

Int. Cl. D8—05

U.S. Cl. D8—30

Fig. 1

Fig. 3

Fig. 2

Fig. 4

Fig. 6

Fig. 5

Fig. 7

Fig. 9

Fig. 8

FIG. 1 is a side elevational view of a first species of an air blowing-vacuuming desoldering appliance or the like embodying my new design, the opposite side elevational view being, in all species, a mirror image of that illustrated;

FIG. 2 is a bottom view thereof;

FIG. 3 is a frontal view thereof;

FIG. 4 is a side elevational view of a second species thereof;

FIG. 5 is a bottom view thereof;

FIG. 6 is a frontal view thereof;

FIG. 7 is a side elevational view of a third species thereof;

FIG. 8 is a plan view thereof; and

FIG. 9 is a frontal view thereof.

I claim:

The ornamental design for an air blowing-vacuuming desoldering appliance or the like, substantially as shown and described.
